KEY BLANK

Walter Edwin Best, Seattle, Wash., assignor to Best Lock Corporation, Indianapolis, Ind., a corporation of Delaware

Filed May 1, 1963, Ser. No. 74,689

Term of patent 14 years

(Cl. D50—4)

FIG. 1

FIG. 2

FIGURE 1 is an elevational view of a key blank showing my new design, the two sides of the bow of said key blank being identical.

FIG. 2 is an edge view of the same.

This application is a continuation in part of my prior application Serial Number D-69,916, filed April 24, 1962 and abandoned concurrently with the filing of this application.

The dominant features of my design reside in the portions shown in full lines.

The space within the uppermost diamond shaped outline is open. The two surfaces scored by diagonal lines and the line shaded area between these two scored surfaces are slightly depressed.

I claim:

The ornamental design for a key blank, substantially as shown and described.
